UNITED STATES PATENT OFFICE

LAURA R. VINDING, OF CHICAGO, ILLINOIS

FOLDING TABLE

Application filed November 24, 1930. Serial No. 497,753.

This invention relates to a folding table and has special reference to a work table which may be folded into a compact unit for storing when not in use.

More particularly, this invention relates to a folding table comprising a top arranged into a compartment for receiving in a slideable relation therein a folding ironing board, the remaining portion of the compartment being subdivided for receiving the work to be operated upon and the various accessories for operating upon the work. The top is provided with folding legs of the usual character so that the assembled unit is very compact to fit into a minimum of space when stored.

A great number of people are now living in comparatively small quarters, some occupying but single rooms. It is highly advantageous, therefore, to conserve space and yet have as complete accommodations as possible. When but a single room is used, that room is invariably furnished as a living room or bed room and it is desirable to conceal from view those objects foreign to a living room.

The present invention has reference to an object of great utility which has uses that may be taken advantage of almost daily. An ironing board of substantial size is slidably contained within the compartment formed by the table top, a space therein being reserved for a sewing machine to rest and the remaining space being subdivided for use in storing the various materials necessary for sewing, mending, pressing, fitting, etc.

It is also pointed out that inasmuch as desirable commercial floor space is so valuable, dressmakers and tailors will have use for a device of this invention because of their small quarters made necessary by the high cost of renting. It is quite desirable when fitting garments to have a maximum of space free from fixtures of any kind in which to view the subject. The work table should be capable of being stored or of being readily accessible at a moment's notice. It is believed the structure of this invention accomplishes these above noted results.

One of the objects of this invention is to

provide a device of the type indicated above wherein the table top is so constructed and arranged as to receive in slideable relationship and to house a folding ironing board and accessories for tailoring and like vocations. 55

Another object of this invention is to provide a device of the character above described which is readily accessible for use or for storage in a minimum of space.

A further object of this invention is to provide a device of the above mentioned character which will be simple in operation, comparatively inexpensive to manufacture, and durable.

Other objects and advantages will herein-after be more particularly pointed out and for a more complete understanding of the characteristic features of this invention, reference may now be had to the following description when taken together with the accompanying drawings, in which latter:

Fig. 1 is a perspective view of the device of this invention when the ironing board thereof is in an extended condition;

Fig. 2 is a vertical sectional view taken on the line 2—2 of Figure 1;

Fig. 3 is a view similar to Figure 1 showing the ironing board therefor housed in its compartment;

Fig. 4 is a vertical sectional view taken on the line 4—4 of Fig. 3;

Fig. 5 is a view similar to Fig. 4 taken on the line 5—5 of Figure 1;

Fig. 6 is a perspective view of a fragmentary portion of the pivotal connection between the table and the folding leg; and

Fig. 7 is a sectional view taken on the line 7—7 of Fig. 2, showing a changed position thereof in dotted lines.

Referring now more particularly to the drawings, the device of this invention is illustrated as comprising a table top 10 formed of a preferably rectangular frame 11 having a top 12 and a bottom 13 therefor. The compartment thus formed by the top, bottom and side wall or frame members is further subdivided by means of partitions 14 and 15 into sub-compartments. It, of course, is to be understood that the number of these sub-compartments may be varied at the will of the 100

manufacturer or user, depending upon the type of employment to which the device may be adapted by the user.

Into one of the elongated pockets, a folding ironing board 16 is housed, the ironing board having a slidable relation with the table top that it may be moved into and out of position in its sub-compartment as would a drawer in a table. An auxiliary support 17 is likewise housed in the same sub-compartment as the ironing board 16 and is moved into and out of engagement therewith because of its relation with the ironing board 16 in a manner which will hereinafter be described.

The ironing board 16 is preferably formed of a plurality of members which are connected together in a folded relation when assembled within the compartment but are adapted to be coextensive in one plane when extended out of the compartment. In the present instance, the ironing board is comprised of two sections 18 and 19 pivotally connected together by means of a pair of hinges 20 and 21, which latter are disposed on the underneath side of the sections when in an extended position. In this position of the hinges the underneath sides of the sections may be folded to lie adjacent each other although they are prevented by the hinges from being extended further apart than in a straight line, the latter being their normal extended position. It is to be understood, of course, that several sections may be employed and hinged together in this manner depending upon the length of the compartment into which they must be made to fit.

The ironing board is prevented from being pulled entirely from without the sub-compartment by means of a pair of stop members 22 which extend from opposite sides at the end of the ironing board and engage grooves 23 at the top of the frame member 11 and at the top of the partition 15, the slots being terminated near the end of the frame and partition members. The ironing board is thus fixed in a slidable relation with the table top, the table top offering a support for one end of the ironing board.

As an auxiliary means for supporting the ironing board, the support 17 is provided and comprises a pair of spaced leg members 24 and 25 pivotally supported at one of the ends thereof to a spacing member 26, which latter is fixedly mounted as by means of the screws 27 to the underneath side of the ironing board section 18. The other ends of the legs 24 and 25 are tied together by means of a tie rod 28 having one end of a brace 29 pivotally connected thereto, the brace comprising a pair of hingedly connected sections 30 and 31. The end of the section 30 is spaced centrally of the legs 24 and 25 by means of spacers 27a and 27b. The upper end of the section 31 is adapted

to engage a recess or other suitable catch member in a disengageable relation for supporting the outer free end of the ironing board.

The brace 29, as we have hereinbefore stated, is formed of two parts, namely, the sections 31 and 30, which latter are pivotally connected together by the hinge 32. The hinge 32 comprises a pair of leaf members 33 and 34 having lugs 35 and 36, respectively, serrated and deformed to extend into a recess 37 formed at the ends of the sections 30 and 31. A coil spring 38 is secured between the lugs 35 and 36 to hold the sections 30 and 31 in either of two extreme positions shown in Fig. 7, that is, in a coextensive relation with each other or in a position folded back upon each other. It is readily apparent that a coil spring will perform this function inasmuch as in any other relation the coil spring must be extended and in either of the two above mentioned positions, the spring extends between the points having the shortest distances.

A small pressing board 39 is disposed in the space afforded by the spacing member 26 and extends in the same direction as the ironing board 16 and just below the same, the pressing board being pivoted to swing out from beneath the ironing board 16 at right angles thereto when desired for use. When not in use the board 39 is moved into position beneath the ironing board 16 on its pivot.

When it is desired to store the table, the section 31 is removed from its securing element on the underneath side of the section 19 and folded back on the section 30. These two folded members as a unit comprise the brace 29 and are next pivoted on the tie rod 27 into a substantial plane with the auxiliary support 17, which latter comprises the depending legs for engagement with the floor. The section 19 is thereafter folded back upon itself and the auxiliary support 17 is raised to extend in the same direction as the ironing board 16, whereafter all of these elements as a unit, are moved into the sub-compartment formed by the partition 15, the auxiliary support moving along on the slides 40 extending longitudinally of the compartment at the bottom thereof and the ironing board being guided by the movement of the pins 22 in the slots 23. A door 16a may close the opening to the compartment.

When it is desired to use the ironing board 16, the unit including the auxiliary support 17 and the brace 29 is pulled outwardly to a position such that the stop members 22 engage the ends of the slots 23. In this position the spacing member 26 depending from the ironing board section 18 extends without the housing and the auxiliary support 17 is pivoted downwardly therefrom, the ends of the racks 24 and 25 engaging

- the floor. The brace 29 is thereafter pivoted on the tie rod 22 and the section 31 moved outwardly against the tension of the compression spring 38 until its occupies a plane coextensive with the section 30, the upper 5 end of the section engaging the underneath side of the ironing board section 19 after it is raised to a position coextensive with the ironing board section 18.
- 10 A portion of the table top 12 above the compartment in which the ironing board unit is adapted to slide has a removable cover 41 which, when removed, presents a space into which the usual hand-sewing machine may be disposed. The other portion of the cover 15 of the table top may be pivotally secured as by means of hinges 42 to the frame 11 so that the cover may be raised to remove the materials kept in the sub-compartments.
- 20 It may be desirable to pivotally mount the legs of the table in order that the table may be folded into a compact unit for storing when not in use. Therefore, a substantially U-shaped bracket 43 for each leg is secured 25 to the frame members 11, one of the legs 44 being pivotally secured in the U-shaped portion by means of the screw bolt 45. When it is desired to hold the leg in an upper position in a line with the frame members, a 30 spring pressed pin 46 is adapted to engage the underside of the leg 44 and when the leg is in a depending position the pin 46 extends through an aperture in the leg 44.
- 35 As a result of this invention a table is provided which may be folded into a compact unit or may be extended to accommodate various types of work. An ironing board is moved into and out of a compartment formed in the table top, the ironing board being 40 formed of a plurality of members and having a support therefor likewise of a plurality of members extending within the same compartment when in condition for storage. Further, the compartments are readily accessible 45 for use in storage materials, and the like, and a compartment is afforded into which a hand-sewing machine may be disposed.
- 50 While but a single embodiment of this invention is herein shown and described, it is to be understood that various modifications 55 thereof may be apparent to those skilled in the art without departing from the spirit and scope of this invention and, therefore, the same is only to be limited by the scope of the prior art and the appended claim.
- I claim:
- 55 In a device of the character described, a portable table having a compartment beneath the top thereof, an ironing board coextensive with the length of said compartment and housed therein, said table top having a covered opening above said compartment and said ironing board having slidable engagement with the walls of said compartment and movable to an operable position on 60 the outside thereof whereby said compartment may receive therein a portable sewing machine through said opening with the top of the table substantially flush with the top of the base of said sewing machine.
- 65 In witness whereof, I have hereunto subscribed my name.
